US00D846153S

(12) **United States Design Patent** (10) **Patent No.:** **US D846,153 S**
de Deugd et al. (45) **Date of Patent:** **** Apr. 16, 2019**

(54) **TRUSS**

(71) Applicant: **PROLYTE GROUP B.V.**, Leek (NL)

(72) Inventors: **Ruud de Deugd**, Assen (NL); **Bart Roelen**, Prinsenbeek (NL); **Gerrit de Beuze**, Zoetermeer (NL)

(**) Term: **15 Years**

(21) Appl. No.: **35/503,425**

(22) Filed: **Mar. 24, 2017**

(80) **Hague Agreement Data**

Int. Filing Date: **Mar. 24, 2017**

Int. Reg. No.: **DM/096903**

Int. Reg. Date: **Mar. 24, 2017**

Int. Reg. Pub. Date: **Jul. 28, 2017**

(51) **LOC (11) Cl.** **25-02**

(52) **U.S. Cl.**

USPC **D25/61**

(58) **Field of Classification Search**

USPC D25/61; D8/354

CPC E04B 1/1903; E04B 3/08; E04B 1/18

See application file for complete search history.
